CLAIM

The ornamental design for a motorcycle helmet, as shown and described.

DESCRIPTION

FIG. 1 is a left side perspective view of a motorcycle helmet showing my new design, which is a mirror image of a right side perspective view;

FIG. 2 is a front view thereof;

FIG. 3 is a top view thereof;

FIG. 4 is a left side view, which is a mirror image of a right side view thereof; and,

FIG. 5 is a back right side perspective view thereof, which is a mirror image of a back left side perspective view thereof.
